MOBILE CHRISTMAS TREE

Raymond Fred, 705 Bradley Road,
Lake Forest, Ill. 60045

Filed Apr. 6, 1973, Ser. No. 348,727

Term of patent 14 years

Int. Cl. D11—01

U.S. Cl. D29—1 A

FIG. 1

FIG. 3

FIG. 1 is a perspective view of an assembled mobile Christmas tree showing my new design;

FIG. 2 is a side elevational view thereof; and

FIG. 3 is a top plan view.

I claim:

The ornamental design for a mobile Christmas tree, substantially as shown and described.
